Primary Examiner — Eliza Z Bennett-Hattan(74) Attorney, Agent, or Firm — Burr & Brown, PLLCCLAIM

The ornamental design for a massage appliance, as shown and described.

DESCRIPTION

FIG. 1 is a front perspective view of a massage appliance illustrating my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines are directed to unclaimed portions of the massage appliance. All broken lines form no part of the claimed design.
